UNITED STATES PATENT OFFICE.

RUDOLF C. BECHER, OF FORT DODGE, IOWA.

HARNESS ORNAMENT.

SPECIFICATION forming part of Letters Patent No. 686,572, dated November 12, 1901.

Application filed July 5, 1901. Serial No. 67,128. (No model.)

To all whom it may concern:

Be it known that I, RUDOLF C. BECHER, a citizen of the United States of America, residing at Fort Dodge, in the county of Webster and State of Iowa, have invented certain new and useful Improvements in Harness Ornaments, of which the following is such a full, clear, and exact description as will enable others skilled in the art to which it applies to make and use the same, reference being had to the accompanying drawings, forming a part hereof.

This invention relates to improvements in ornaments for face-drops, hip-straps, blinders, and other parts of harness; and it consists in a certain novel construction and combination of parts, which will be hereinafter first fully described and then particularly pointed out in the claims.

In the accompanying drawings, which fully illustrate my invention, Figure 1 is a plan view of the ornament, and Fig. 2 is a diametrical section thereof.

For convenience of illustration I have shown the ornament applied to a blinder, (designated by the letter A.) Placed against the face of the leather composing the blinder is a glass setting B, having a convex face and provided with a polished metallic backing C, which will reflect the light passing through the setting, and thereby impart brilliancy to the setting. Encircling the setting is a ring D, which is circular in cross-section and is of such a diameter as to project over the edge of the setting, and thereby hold it to the leather. This ring is secured to the leather by small screws, headed nails, or similar fastenings E, which are inserted through the leather into the ring, as clearly shown. The ring may be made of celluloid, light wood, or some similar material, and in order to increase the effectiveness of the device the set-

ting is usually colored and the ring given a color which will form a marked contrast with the setting.

It will be seen at once that I have provided an ornament which is exceedingly simple and which may be quickly applied to any harness. The setting rests against the leather, so that there is no space between the leather and the setting, and consequently there is no falling or buckling of the leather at that point. By utilizing headed screws or similar fastenings to secure the ring to the leather I avoid the provision of projections which irritate the animal and prevent the proper adjustment of the harness.

The device is very light and effectively relieves the monotony of an extended unbroken surface of leather.

Having thus described my invention, what I claim, and desire to secure by Letters Patent, is—

1. A harness ornament consisting essentially of a setting resting against the leather, a ring also resting against the leather and projecting over the edge of the setting, and headed fastenings inserted through the leather into the ring.

2. A harness ornament consisting of a glass setting resting against the leather of the harness, a ring also resting against the leather, said ring being circular in cross-section and having its inner convexity projecting over the edge of the setting, and fastenings inserted through the leather into the ring.

In testimony whereof I have signed this specification in the presence of two subscribing witnesses.

RUDOLF C. BECHER.
